CLAIM

The ornamental design for a combined dispensing applicator and cover therefor, as shown and described.

DESCRIPTION

FIG. 1 is a top plan view of a combined dispensing applicator and cover therefor showing my new design, the cover being omitted for clarity of illustration only; FIG. 2 is a bottom plan view thereof; FIG. 3 is a right side elevational view thereof, the left side being a mirror image; FIG. 4 is a front elevational view thereof; FIG. 5 is a rear elevational view thereof; FIG. 6 is a top plan view thereof, shown with the cover in place on the applicator; FIG. 7 is a bottom plan view thereof; FIG. 8 is a right side elevational view thereof, the left side being a mirror image; FIG. 9 is a front elevational view thereof; and FIG. 10 is a rear elevational view thereof; and FIG. 11 is a cross sectional view thereof taken along line 11—11 of FIG. 8.

FIG. 1

FIG. 2

FIG. 5
